CLAIM

The ornamental design for “shovel,” as shown and described.

DESCRIPTION

FIG. 1 is a perspective view showing a first embodiment of a “shovel” incorporating the design of my invention;

FIG. 2 is a top view thereof;

FIG. 3 is a side view thereof;

FIG. 4 is an opposite side view thereof;

FIG. 5 is a bottom side view thereof;

FIG. 6 is a rear view thereof;

FIG. 7 is a front view thereof; and,

FIG. 8 is a perspective view showing an alternate position of a shovel incorporating the design of my invention.
